FIG. 8

In the drawings:

FIGURE 1 is a perspective view of a combined fryer and storage locker showing my new design seen from one side in open position while FIGURE 2 is a perspective view of the same design seen from the other side in closed position;

FIGURE 3 is a perspective view of a modified form thereof seen from one side in open position and FIGURE 4 is a perspective view thereof seen from the other side in closed position;

FIGURE 5 is a perspective view of a further modified form thereof seen from one side in open position and FIGURE 6 is a perspective view of the same seen in closed position from the other side; and

FIGURE 7 is a perspective view of another modified form thereof seen from one side in open position and FIGURE 8 is a perspective view thereof seen from the other side in closed position.

The common characteristic feature of these embodiments reside in the location of the handle, the same being at the rear of the cover when same is open.

I claim:

The ornamental design for a combined fryer and storage locker, as shown and described.
